(No Model.)

L. V. GILLILAND.
CARPET RAG LOOPER.

No. 575,031.

Patented Jan. 12, 1897.

UNITED STATES PATENT OFFICE.

LAURA V. GILLILAND, OF DAVENPORT, NEBRASKA.

CARPET-RAG LOOPER.

SPECIFICATION forming part of Letters Patent No. 575,031, dated January 12, 1897.

Application filed March 23, 1896. Serial No. 584,503. (No model.)

To all whom it may concern:

Be it known that I, LAURA V. GILLILAND, a citizen of the United States, residing at Davenport, in the county of Thayer and State 5 of Nebraska, have invented a new and useful Carpet-Rag Looper, of which the following is a specification.

This invention relates to carpet-rag loopers; and the object in view is to simplify and 10 improve the construction of articles of this character and to provide one in which the point of the needle may be withdrawn into a recess in which it will be entirely covered and protected, not only protecting the person from 15 injury, but saving the point of the needle smooth and in perfect condition for use when again desired.

The invention also has for its object to provide novel means for holding the needle extended, the said means being automatic in 20 action, requiring no attention on the part of the operator.

The invention consists of an improved carpet-rag looper embodying certain novel features and details of construction, as herein-after fully described, illustrated in the drawings, and finally pointed out in the claim here-to appended.

In the accompanying drawings, Figure 1 is 30 a perspective view of the improved looper. Fig. 2 is a vertical transverse section through the same. Figs. 3, 4, 5, and 6 show the different steps in the method of forming a loop.

Similar numerals of reference designate cor- 35 responding parts in the several figures of the drawings.

Referring to the accompanying drawings, 1 designates a metal case having therein a 40 longitudinal bore corresponding to the cross-sectional shape of and adapted to receive slid- 45 ingly an extensible needle or looper 2. The needle is provided at its advance end with the usual point 3 and eye 4, and at its opposite end it has a lateral projection 5, forming a finger-hold, by means of which the needle 50 may be moved lengthwise. The projection 5 extends outward through a longitudinal slot 6 in the front wall of the case 1, such slot being of a length sufficient to allow the point of 55 the needle to be withdrawn entirely within the upper end of the case 1, and also to be extended into operative position, as shown in

Fig. 1. The slot 6 is of less width than the case 1, so as to leave longitudinal side ledges 7, behind which the needle slides. The pro- 55 jection 5 limits the longitudinal movements of the needle and prevents the entire withdrawal thereof from the case.

Within the bore of the case is arranged a leaf-spring 8, fast at its lower end in the bot- 60 tom of the slot 6, and having its free end located near the upper end of the slot and provided at such free end with an L-shaped bend or offset, as indicated at 9.

When the needle is extended to its outer- 65 most position, the free end of the spring snaps under the lower or butt end of the needle and thereafter prevents the accidental dropping of the needle, while the offset 9 strikes against the side of the needle and constitutes a stop 70 for limiting the outward vibration of the spring.

When it is desired to withdraw the needle into the case, the spring 8 may be pressed in- 75 ward by one finger and the projection 5 oper- ated by another finger. When the needle has been drawn inward in the manner de- 80 scribed, the spring 8 will exert its tension to prevent the accidental outward movement of the needle. The projection 5, while being 85 amply sufficient to enable the operator to ex- tend and withdraw the needle, does not, how- ever, afford any substantial projection or ob- struction which would interfere with the operator or cause injury to the hands. 85

Upon its rear side the case 1 has parallel arms or ears 10, one of which is threaded to receive a thumb-screw 11, whereby the device may be clamped upon the edge of a table.

In operation the looping device is clamped 90 upon a table, as described. The ends of the pieces or strands to be united are overlapped, as shown in Fig. 3, and grasped between the thumbs and forefingers of the operator's hands and passed down over the point of the 95 needle and below the eye thereof, as shown in Fig. 4. The opposite or free end of the lower piece or strand is now passed through the eye of the needle, as in Fig. 5, after which the lapped ends are drawn upward off the 100 needle, thereby leaving the free end of the lower piece or strand threaded through the punctures made by the needle in the lapped ends, as shown in Fig. 6. Grasping the outer

ends of the two pieces, the connection is now drawn taut, thus forming a strong and effect-
ive union between the adjacent ends, leaving no projecting ends and dispensing with the
necessity for the use of thread and the labo-
rious work of stitching the ends together.
After the work has been completed the loop-
ing device may be removed from the table
10 and the needle drawn inward, where its point
will be protected from contact with mois-
tened fingers, being thus kept in prime con-
dition for further use.

Changes in the form, proportion, and minor
details of construction may be resorted to
15 without departing from the spirit or sacrific-
ing any of the advantages of this invention.

Having thus described the invention, what
is claimed as new is—

A carpet-looper, comprising an oblong case
20 having a longitudinal bore or recess, a needle
slidably mounted therein and provided at its

inner end with a lateral projection, the case
being provided with a slot in one side com-
municating with the inner end of the bore
and terminating short of the ends of the case,
25 a leaf-spring located in said bore and arranged
opposite the said slot in the case whereby it
may be pressed inward by the finger for re-
leasing the needle, the said spring having its
free end offset to form a shoulder for engag-
ing the heel end of the needle when thrust
outward, and provision for securing the
looper to a suitable support, substantially as
described.

In testimony that I claim the foregoing as 35
my own I have hereto affixed my signature in
the presence of two witnesses.

LAURA V. GILLILAND.
